DESIGN FOR A MECHANICAL PENCIL

Paul S. Hauton, Atlanta, Ga.

Application May 6, 1933, Serial No. 48,030

Term of patent 14 years

To all whom it may concern:

Be it known that I, PAUL S. HAUTON, a citizen of the United States, residing at 423 Houston Street, in the city of Atlanta, in the county of Fulton, and State of Georgia, have invented a new, original, and ornamental Design for Mechanical Pencils, of which the following is a specification, reference being had to the accompanying drawing, forming part thereof.

Fig. 1 is a front elevation of a mechanical pencil showing my new design; and Fig. 2 is a side elevation of the same.

I claim:

The ornamental design for a mechanical pencil, as shown.

PAUL S. HAUTON.
